Fig. 7

We claim:

The ornamental design for a display sign or similar article, substantially as shown.
